CLAIM

The ornamental design for a set of bidding cards for the card game of bridge, as shown and described.

DESCRIPTION

FIG. 1 is a top plan view of the front faces of one group of bidding cards for the no trump bidding, part of the set of bidding cards for the card game of bridge, showing my new design;

FIG. 2 is a bottom plan view of FIG. 1, showing the charts of point values for the bidding;

FIG. 3 is a top plan view of the front faces of a second group of bidding cards for the spade suit of bidding;

FIG. 4 is a top plan view of the front faces of a third group of bidding cards for the heart suit of bidding;

FIG. 5 is a top plan view of the front faces of a fourth group of bidding cards for the diamond suit of bidding;

FIG. 6 is a top plan view of the front faces of a fifth group of bidding cards for the club suit of bidding;

FIG. 7 is a bottom plan view of FIG. 4, showing the charts of point values for the bidding; the backs of the cards shown in FIG. 3 being identical, but with narrower tabs on the top edge as shown in FIG. 3;

FIG. 8 is a bottom plan view of FIG. 5, showing the charts of point values for the bidding; the backs of the cards shown in FIG. 6 being identical, but with full width tabs on the top edge, as shown in FIG. 6;

FIG. 9 is a plan view of the complete set of bidding cards assembled in a package;

FIG. 10 is a left side edge view of the package of cards shown in FIG. 6;

FIG. 11 is a right side edge view of the package of cards shown in FIG. 9;

FIG. 12 is a bottom edge view of the package of cards shown in FIG. 9; and,

FIG. 13 is a top edge view of the package of cards shown in FIG. 9.

Fig. 1

Fig. 2 displays seven tables, one for each panel in Fig. 1, showing data for 'PASS', 'XX', and 'N' categories.

Panel 1 Data:

	PASS	XX	N
-	90	180	560
+1	120	280	760
+2	150	380	960
+3	180	480	1160
+4	210	580	1360
+5	240	680	1560
+6	270	780	1760

Panel 2 Data:

	PASS	XX	N
-	40	80	120
+1	430	850	1000
+2	460	750	1200
+3	490	850	1400
+4	520	950	1600

Panel 3 Data:

	PASS	XX	N
-	400	800	1200
+1	430	850	1150
+2	460	750	1050
+3	490	850	1400
+4	520	950	1550

Panel 4 Data:

	PASS	XX	N
-	400	800	1200
+1	430	850	1150
+2	460	750	1050
+3	490	850	1400
+4	520	950	1550

Panel 5 Data:

	PASS	XX	N
-	400	800	1200
+1	430	850	1150
+2	460	750	1050
+3	490	850	1400
+4	520	950	1550

Panel 6 Data:

	PASS	XX	N
-	400	800	1200
+1	430	850	1150
+2	460	750	1050
+3	490	850	1400
+4	520	950	1550

Panel 7 Data:

	PASS	XX	N
-	400	800	1200
+1	430	850	1150
+2	460	750	1050
+3	490	850	1400
+4	520	950	1550
